SERVICE COUNTER FOR BANKS

Francis C. Kegel, Kenmore, N.Y., assignor to APF Industries, Inc., Buffalo, N.Y., a corporation of New York

Filed July 11, 1961, Ser. No. 65,876

Term of patent 14 years

(Cl. D80—2)

Fig. 1.

Fig. 2.

Fig. 3.

Fig. 4.

Fig. 6.

Fig. 5.

FIG. 1 is a perspective view of a service counter for banks embodying my new design.

FIG. 2 is a front elevational view thereof.

FIG. 3 is a top plan view thereof.

FIG. 4 is a rear elevational view thereof.

FIG. 5 is a bottom plan view thereof.

FIG. 6 is a right end elevational view thereof; the opposite left end elevational view thereof being substantially the same.

The rectangular panel in the center of the top is stippled to indicate contrast.

I claim:

The ornamental design for a service counter for banks, substantially as shown and described.
